UNITED STATES PATENT OFFICE.

CHARLES EMRY YATES, OF NEAR MILL GROVE, MISSOURI.

CHURN.

SPECIFICATION forming part of Letters Patent No. 657,805, dated September 11, 1900.

Application filed January 17, 1900. Serial No. 1,748. (No model.)

To all whom it may concern:

Be it known that I, CHARLES EMRY YATES, a citizen of the United States, residing near Mill Grove, in the county of Mercer and State 5 of Missouri, have invented a new and Improved Operating Mechanism for Churn-Dashers, of which the following is a full, clear, and exact description.

My invention relates to mechanism for operating churn-dashers.

The object of my invention is to provide a comparatively simple and efficient mechanism of the above-indicated class which may be readily connected with and disconnected 15 from the dasher of an ordinary churn and which may be operated uniformly with small expenditure of power.

Reference is to be had to the accompanying drawings, forming a part of this specification, 20 in which similar characters of reference indicate corresponding parts in all the views.

Figure 1 is a perspective view of the churn complete. Fig. 2 is an end elevation thereof. Fig. 3 is a side elevation with parts in section substantially on the line 3 3 of Fig. 2, 25 and Fig. 4 is a sectional plan view on the line 4 4 of Fig. 3.

A is the churn-body, which may be of any suitable construction and rests upon the base 30 B of the machine.

The cover C is preferably provided with a funnel D, surrounding the rod E of the dasher F and intended to prevent splashing of the milk. The dasher-rod E is provided at regular intervals with apertures E', adapted to be engaged by pins G, secured to a U-shaped cross-head G', which has sleeves G², arranged to slide on a stationary vertical guide H, secured to the post I. The upper member of 35 the cross-head G' is provided with a horizontally-disposed loop G³, (see Figs. 1 and 4,) through which extends a pitman or connecting-rod J, connected with the cross-head at J' and operated by a crank K upon a shaft L, 40 journaled in the post I. This shaft L carries a fly-wheel M and a pulley N, which is driven by means of a transmission-cord O from a large pulley P upon the actuating-shaft Q. This shaft is also journaled in the post I, and 45

50 preferably the end of the shaft also has a bearing in the guide H, said guide having an upward extension or bracket H', in which is

formed an additional bearing for the shaft L. The shaft Q is provided with a crank-handle R, so as to be adapted to be operated by hand. 55 The post I is braced laterally by two inclined or diagonal stays S, extending from the bottom of the guide H to side extensions I' of the post, and, furthermore, a rear brace T is provided, secured to the base B and to the post 60 I, preferably as shown in Fig. 2, by means of the same bolt U which also secures the stays S and the lower end of the guide H to the said post.

The machine is operated by turning the 65 crank R, which causes the cross-head G', and with it the dasher F, to reciprocate up and down, churning the milk in the ordinary way. It will be observed that the dasher-rod is held very securely, since it is fastened to the cross-head G' at two points of its length, and to absolutely prevent any possible disengagement of the dasher-rod from the cross-head 70 a suitable pin V may be passed through apertures provided in the ends of the pins G. 75 It will be understood that the said pins are passed through two of the apertures E' and that the distance between the dasher F and the cross-head G' may be varied by engaging the pins G through appropriate apertures E', 80 so that the machine may be used in connection with churn-bodies of different sizes. The motion of the cross-head G' also is very steady, owing to its being guided by two sleeves or slides G² and owing to its being securely fastened to the dasher-rod. The employment of the fly-wheel M and the particular bracing of the post I also contribute to 85 render the motion steady and uniform.

Having thus described my invention, I 90 claim as new and desire to secure by Letters Patent—

1. In an operating mechanism for churning, the combination of the stationary guide, the cross-head mounted to move on said guide 95 and provided with projections adapted to be connected to a dasher-rod and with a loop extending transversely in relation to the guide, the pitman connected with the cross-head and extending through said loop, and crank mechanism connected with the pitman.

2. In an operating mechanism for churning, the combination of the stationary guide, the cross-head having two spaced slides mounted

to move on said guide and provided with two projections adapted to be connected to a dasher-rod and with a loop extending transversely relatively to the guide, the pitman 5 connected with the cross-head between the two slides and extending through the loop, and crank mechanism connected with the pitman.

In testimony whereof I have signed my name to this specification in the presence of 10 two subscribing witnesses.

CHARLES EMRY YATES.
